REMOTE SHAFT POSITIONER

William F. Carr, Santa Monica, Calif., assignor, by mesne assignments, to Motorola, Inc., Chicago, Ill., a corporation of Illinois.

Filed Sept. 25, 1958, Ser. No. 763,319

5 Claims. (Cl. 318—467)

This invention relates to devices for causing a load-carrying shaft in a remote position to execute a relatively precise predetermined rotation under load. Specifically, the device of this invention is intended to cause the operation of a remotely located, multiple-pole, multiple-contact switch.

In complex electrical and radio apparatus it is often required that a large number of switch contacts be made or broken simultaneously with a minimum of effort and sometimes in a remote location. Quite often the switches are all of the rotary type and may be ganged on a single operating shaft. However, if this is the case, the physical effort required to turn the shaft is often beyond that which can be conveniently furnished by a human operator and also may be greater than that which may be furnished by a solenoid-type stepping motor. Furthermore, since typically for each full revolution of the shaft there exists a large number of switch positions spaced at a few degrees apart around the shaft axis, the rotation of the shaft must be controlled very accurately in order to achieve the desired switching action. If the various switch positions are spaced rather closely around the axis of the shaft, it is possible that any powerful motor device which might be selected to drive the shaft would, due to its own inertia, tend to carry the shaft beyond the preselected position at which it might be desired that the motor and shaft stop.

This invention has for its principal object the provision of a simple, powerful and positive means for remotely positioning accurately a load-carrying shaft.

Another object of this invention is to provide means for effecting accurate remote positioning of ganged multiple-contact switches.

It is another object of this invention to provide an accurate remote indexing device.

Other objects of invention will become apparent from the following description taken in connection with the accompanying drawings, in which

Fig. 1 is a plan schematic view of the invention;

Fig. 2 is a sectional view of the invention, taken at 2—2 in Fig. 1;

Fig. 3 is a partial sectional view of the invention taken at 3—3 in Fig. 1; and

Fig. 4 is a partial sectional view of the invention taken at 4—4 in Fig. 1.

Referring now to the drawing, there is shown a motor 1 connected at one terminal to a battery 2, or other source of power. Motor 1 is mechanically connected through a gear train 3 to a gear 4, which drives main gear 5. Main gear 5 is rotatable upon a shaft 6 and has integrally attached to it an eccentric circular cam 7, as shown. Cam 7 carries cam follower 8, having arms 9 and 10 extending therefrom, as shown. Follower 8 is free to rotate upon cam 7, except that Belleville spring 11 shown in Fig. 2 being somewhat compressed, causes the frictional engagement of follower 8 and cam 7.

Arm 9 has integrally attached to it a drive pin 12 adapted to engage the teeth 13 of ratchet wheel 14, which

2

is carried for rotation upon a shaft 15. Shaft 15 is arranged to rotate a plurality of ganged switches 16, or other mechanical load. Shaft 15 also drives a rotatable switch wafer 17 about which are positioned multiple fixed contacts, such as 18, 19, 20, 21, 22, 23, 24 and 25. Contacts 18 through 25 are in turn connected to contact points 26, 27, 28, 29, 30, 31, 32 and 33 on remote selector switch 34 having a rotatable contact arm 35.

For purposes to be hereinafter explained, it is preferable that the number of contacts about wafer 17, as well as the number of contacts on selector switch 34 and the number of teeth of ratchet wheel 14, be the same or be multiply related.

Ratchet wheel 14 and shaft 15 are caused to rotate in discrete steps corresponding to a single tooth position of the ratchet gear and a single switch position of selector switch 34 by means of wafer spring 36 held in fixed position by means of bolts 37 and 38. Wafer spring 36 incorporates gear members 39 and 40 having holes 41 and 42 therein. Holes 41 and 42 contain small steel balls 43 and 44 which rest in detents 45 in detent plate 46 which is attached to shaft 15 and rotates therewith.

Motor 1 is also connected to wafer 17 by any permanent means, such as a slip ring, and battery 2 is arranged by the connections, as shown, to energize solenoid 47 whenever motor 1 is energized. Solenoid 47 is mounted adjacent main gear 5 and cam follower 8, as shown, and incorporates a plunger 48 whose normal position is extended as shown in Fig. 3. The solenoid and shafts 6 and 15 are preferably arranged to be supported on the same frame and to be maintained in a fixed physical relationship. Plunger 48 of solenoid 47 is positioned so as to interfere with the motion of arm 10 of follower 8 unless current is applied to the solenoid.

In operation the device functions as follows. Selector switch 34, being at a remote position, may be rotated so that rotatable contact 35 touches any one of the fixed contacts. Assuming that the operator, just prior to the time depicted by Fig. 1, has moved the selector switch 40 so that rotatable contact 35 touches fixed contact 31, it can be seen that current flows from battery 2 through arm 35 to contact 31, thence to contact 18, wafer 17, and back to the motor. The motor therefore rotates. At the same time, it can be seen that current flows through the 45 winding of solenoid 47, causing plunger 48 to be withdrawn clear of arm 10. Gear 5 is caused to rotate in a counterclockwise direction in Fig. 1 by the action of motor 1, gear train 3, and gear 4. Cam follower 8 therefore moves to the right in Fig. 1, as shown, causing pin 50 12 to engage a tooth of ratchet gear 14 which advances the gear one gear tooth and causes ganged switches 16 and wafer 17 to be advanced by the same increment. The motion of ratchet wheel 14 and shaft 15 is likewise counterclockwise. However, when this step has been

55 completed it can be seen that current still flows to the motor. Accordingly, the ratchet wheel continues to be advanced one tooth position for each rotation of main gear 5. This process continues until notch 56 in wafer 17 comes to rest on the particular contact through which 60 power is supplied to motor 1. In this case that contact is contact 18 and corresponds to the selector switch position chosen for switch 34. At this point, current no longer flows to motor 1 and solenoid 47, so two things happen. First of all, motor 1 coasts to a stop. However, 65 before this can happen, solenoid 47 is de-energized, releasing plunger 48 which immediately interferes with the motion of arm 10 of follower 8. For each revolution of main gear 5, it can be seen from Fig. 1 that arm 10 oscillates from a position which is non-interfering with respect to the position of plunger 48 to a position which is interfering. Accordingly, although main gear 5 may 70 continue to rotate because of the inertia of motor 1 and

gear train 3, after current is interrupted, the very next attempt which cam follower 8 makes to advance ratchet gear 14, the solenoid plunger interferes with the necessary motion and cam 12 fails to engage the ratchet wheel. The positions which pin 12 and arm 10 occupy when plunger 48 is in interfering position are shown by dotted lines in Fig. 1. When plunger 48 blocks movement of arm 10, the only force withstood by the solenoid plunger is that caused by the friction of Belleville spring 11 against follower 8, as shown in Fig. 2.

While ganged switches commonly employ some type of detent mechanism which assures that the switch stops at discrete positions, assuring optimum electrical contact between the rotatable member and the fixed switch contacts, it is also possible to incorporate such a detent mechanism with the ratchet wheel assembly as shown in Fig. 4. In Fig. 4, detent plate 46 has cut in it a number of holes corresponding to the number of switch positions or discrete shaft positions desired, and balls 43 and 44 are caused to deflect gears 41 and 42 of leaf spring 36 which is fixedly supported at 37 and 38, as shown. Any comparable detent indexing device well-known in the art may be utilized so long as it assures the motion of ratchet wheel 14 in discrete steps.

It should be understood that the eccentricity of cam 7, the length of arm 9, the depth and dimensions of ratchet wheel teeth 13 must be coordinated so that the motion of the cam follower for each revolution of main gear 5 is just that required to advance the ratchet wheel one tooth position. Likewise, it is possible, of course, to have a number of teeth on ratchet wheel 14 which is any even multiple of the number of switch positions or discrete shaft positions desired. For example, as shown in Fig. 1, the device takes care of eight remote switch positions. To accomplish this result it is contemplated that a minimum of eight teeth are required on ratchet wheel 14. However, the same result would be accomplished by the use of 16 teeth on ratchet wheel 14.

Since virtually any size motor may be used as motor 1, this motor being either an alternating-current motor or a direct-current motor with a suitably substituted alternating-current source in place of battery 2, in case of the alternating current motor, and since gear train 3 may be selected to provide any desired mechanical advantage, it can be seen that substantial torque can be made available on shaft 15 to turn ganged switches 16, or any other device which needs to be indexed, at discrete preselected positions corresponding to the various positions of switch 34.

By the use of a solenoid 47 it is seen that the possibility of the device overshooting the desired index position, as determined by selector switch 34, is positively eliminated since follower 8 becomes inoperative to advance ratchet heel 14 the moment power to motor 1 and solenoid 47 is interrupted by virtue of switch 15 reaching the desired preselected position.

Although the invention has been described and illus-

trated in detail, it is to be clearly understood that the same is by way of illustration and example only and is not to be taken by way of limitation, the spirit and scope of this invention being limited only by the terms of the appended claims.

I claim:

1. In combination, an n-position rotary switch, an n-tooth ratchet gear connected to drive said switch, a rotatable shaft, eccentric means attached to said shaft, follower means frictionally engaging said eccentric means and having an arm periodically engaging said ratchet gear to rotate it one tooth position for each revolution of said shaft, a second arm on said eccentric means, plunger means normally engaging said second arm to prevent said first arm from engaging said ratchet gear, solenoid means for disengaging said plunger means when energized, a motor driving said shaft, and switch means operable by said ratchet gear for energizing said motor and solenoid until said ratchet gear has been rotated to a predetermined position.

2. In combination a motor, a rotatable shaft driven by said motor, an n-tooth ratchet gear connected to a switch shaft, eccentric means attached to said rotatable shaft, follower means frictionally engaging said eccentric means and having an arm periodically engaging said ratchet gear to rotate it one tooth position for each revolution of said shaft, a second arm on said follower means, plunger means normally engaging said second arm to prevent said first arm from engaging said ratchet gear, solenoid means for disengaging said plunger means when energized, and switch means connected to said switch shaft for energizing said motor and solenoid until said ratchet gear has been rotated to a predetermined position.

3. The device as claimed in claim 2 in which the switch means includes a multi-position rotary switch having a rotor with an electrical contact point corresponding to all but one of the multiple positions.

4. The device as claimed in claim 3 in which said switch means also includes a remote selective-type switch and wherein an electrical potential is connected to said motor and said solenoid by way of said multi-position rotary switch and said remote switch such that said remote switch connects said electrical potential to any one of the contacts on the stator of said multi-position switch and said motor drives said shaft until the non-conductive portion of said rotor engages the selected contact of said stator, thereby causing said motor and said solenoid to be de-energized.

5. The device as claimed in claim 4 further including at least one n-position rotary switch connected and driven by said switch shaft.
